UNITED STATES PATENT OFFICE.

THOMAS A. KILLMAN, OF LIBERTY, TENNESSEE, ASSIGNOR OF ONE-HALF TO
ALVIN E. POTTER, OF SAME PLACE.

COMPUTING-SCALE.

SPECIFICATION forming part of Letters Patent No. 655,629, dated August 7, 1900.

Application filed May 17, 1900. Serial No. 17,038. (No model.)

To all whom it may concern:

Be it known that I, THOMAS A. KILLMAN, a citizen of the United States, residing at Liberty, in the county of De Kalb and State of 5 Tennessee, have invented a new and useful Computing-Scale, of which the following is a specification.

The invention relates to improvements in computing-scales intended for use by store- 10 keepers and others for the purpose of automatically figuring and indicating the cost of goods at different rates per pound.

An object of the present invention is the provision of such an apparatus which will possess the advantage of simplicity and cheapness in construction as compared with prior structures of its class and which at the same time is reliable and certain in operation.

A further object of the invention is to provide an improved construction in which is employed a dial that will not be subjected to jarring or vibration produced by the use of the scale, and, furthermore, to house and protect the working parts of the scale and the 25 computing mechanism thereof from accumulations of dirt and from insects.

With these ends in view the invention consists in the construction and novel combination and arrangement of parts hereinafter 30 fully described, illustrated in the accompanying drawings, and pointed out in the claims hereto appended.

To enable others to understand the invention, I have illustrated a preferred embodiment of the same in the accompanying drawings, forming a part of this specification, and in which—

Figure 1 is a perspective view of an ordinary platform weighing-scale embodying a 40 computing mechanism constructed in accordance with this invention. Fig. 2 is an enlarged vertical sectional view illustrating the computing mechanism in detail. Fig. 3 is a vertical sectional view on line 3 3 of Fig. 2. Fig. 4 is a vertical sectional view on line 4 4 of Fig. 2. Fig. 5 is a detail horizontal sectional view taken on the line 5 5 of Fig. 2. Fig. 6 is an enlarged detail view illustrating the construction of the indicating mechanism. Fig. 7 is a 50 detail perspective view of the swinging frame.

The same numerals of reference are used to indicate like and corresponding parts in each of the several figures of the drawings.

The scale-beam 10, which is peculiarly constructed for the accommodation of the computing mechanism of my invention, is hung on an upright or other support 11, the latter being carried by the frame 12. This frame also supports the usual scale mechanism for the platform 13, and this platform scale mechanism is connected with the scale-beam through the intermediate connections 14. These parts are or may be of the usual construction and they need not be further described in this specification. The scale-beam 10 comprises, essentially, a housing or casing 15, a weight-bar 16, a rate-bar 17, and a tare-bar 18, all of which are united or joined firmly together, so as to maintain the three bars in parallel relation. I prefer to arrange the rate-bar 17 at the upper part of the scale-beam and the tare-bar between and equidistant from the weight-bar and the rate-bar, and this beam is furthermore provided with the usual weight-rod 19. The weight-bar 16 is graduated in 75 the ordinary way to indicate the weight of the goods in pounds and ounces and on it is slidably fitted a poise 20. The rate-bar 17 has one or both faces thereof graduated with figures indicative of the price per pound of the 80 merchandise, and the said bar receives a slid- able poise 21. The intermediate tare-bar is graduated and receives the poise 22, as shown in Fig. 1.

The weight-bar 16 of the scale-beam is hol- 85 low longitudinally to form therein a chamber 23, and the lower or under side of this bar is formed with a longitudinal slot 24, the latter communicating with the chamber. A primary nut 25 is fitted slidably in this longitudinal 90 chamber of the hollow weight-bar, so as to be prevented from turning or rotating therein, but at the same time is free to have an end- wise traveling or slidable movement with the counterpoise 20 longitudinally of the weight- 95 bar. This end is attained by making the chamber of the weight-bar and the nut square or angular in cross-section, so as to enable the nut to move freely lengthwise of the cham- ber, and by uniting the nut to the counter- 100

poise 20 through the medium of a fastener 26. This fastener is shown by Figs. 2 and 4 in the form of a screw passing through the poise 20 and into the nut 25, said fastener being adapted to travel in the slot 24 of the weight-bar. A revoluble screw-spindle 27 is arranged in the chamber of the weight-bar, and said spindle has its end portions loosely journaled in suitable bearings provided in said bar for the purpose of mounting the spindle so it may be rotated with ease and freedom by the traveling motion of the nut with the poise. This screw-spindle passes through and has threaded engagement with the nut 25, so that it will be actuated by the nut, and one end of this spindle is projected into the chamber formed by the casing or housing 15, said projecting end of the spindle receiving a crown-gear 28, which is made fast therewith, so as to rotate with the spindle at all times.

29 designates a swinging frame which is disposed within the chamber formed by the casing or housing 15, so as to lie at an angle to the screw-spindle within the weight-bar. At the lower end of the swinging frame it is formed with a footpiece 30, the latter having the laterally-extending studs or pins 31, which are loosely fitted in the sides of the casing or housing 15 in coaxial relation to the fulerum 30 of the scale-beam in the upright or support 11. This frame is pivotally mounted in the housing at a point adjacent to the crown-wheel on the screw-spindle 27 for the purpose of permitting the frame to swing to different positions and angles relative to the axis of the spindle 27 without throwing a secondary spindle 37 on the frame out of gear with the poise-actuated spindle 27. The upper part of the swinging frame is provided with a head-piece 32, which is parallel to the footpiece, said head and foot pieces forming the journal-bearings for the screw-spindle 37, which is arranged longitudinally of the pivotal supporting-frame 29. A secondary traveling nut 33 has threaded engagement with the screw-spindle 37, which is movable with the swinging frame, and this traveling nut is confined in slidable relation to the swinging frame, preferably by fitting one of the faces of the nut against the flat side of the frame, whereby the nut is confined against rotation, but is free to travel longitudinally with respect to the frame and the spindle 37. A bevel gear-wheel 34 is made fast to the lower end of the spindle 37, and this gear-wheel is arranged in such relation to the support of the swinging frame that it will mesh at all times with the crown-gear 28 on the poise-actuated spindle 27, whereby rotation of the spindle 27 under the action of the poise and the nut connected therewith rotates the screw-spindle 37 through the medium of the intermeshing gears 28 and 34 notwithstanding variations in the angular position of the swinging frame to the plane of the longitudinal axis of the poise-actuated spindle. The movable nut 33 of the screw-spindle 37, which is movable with the

swinging frame, is provided with a rack-actuating stud or pin 35, said stud or pin having a slidable relation to an element of the rack to permit the nut to travel freely, as will presently appear.

The tare-bar 18 is provided with longitudinal guideways 36 and 36^a, in which are slidably fitted endwise-movable rack-bars 38 and 38^a, which are free to move longitudinally in the tare-bar. One end of the rack-bar 38 is extended into the chamber or housing 15, and to this rack-bar 38 is firmly secured a cross-head 39, the latter being disposed in the housing to move freely therein back and forth with the rack-bar. This cross-head is arranged at right angles to the rack-bar 38, and the cross-head and the rack-bar are guided by the tare-bar to move in a rectilinear path. The extended end of the rack-bar 38 engages with an element or pinion 60 of an indicator mechanism which is carried by the housing 15 and which may be of any suitable construction. I prefer to employ the indicator mechanism of the type shown in Figs. 1, 3, and 6, in which a dial is secured firmly to a side of the housing and is adapted to be traversed by one or more pointers driven from a train of gears, as hereinafter explained. This rack 38 is actuated by connections between its cross-head and the secondary nut 33, which is propelled by rotation of the screw-spindle 37, driven through intermediate gear connections with the poise-actuated spindle 27, and in the embodiment of the invention herein represented the cross-head 39 is provided with a longitudinal slot 40, adapted to receive the pin or stud 35, which is movable with the traveling nut 33, whereby a loose connection or compensating joint is provided between the traveling nut and the rack-bar 38.

The guideways 36 and 36^a of the tare-bar are separated by an intervening partition 36^b, which is provided between its ends with an opening 36^c, in which is mounted a pinion 38^b, which meshes with the teeth of the rack-bars 38 and 38^a, whereby the rack-bars are moved simultaneously in opposite directions. The rack-bar 38, which is located in the lower guideway 36 of the tare-bar, is provided at its upper edge with teeth which mesh with the pinion 38^b and with the said pinion or element 60 of the indicating mechanism. The upper rack-bar 38^a of the tare-bar is provided at its lower edge with teeth to mesh with the pinion 38^b, and it is adapted to counterbalance or neutralize the effect of the rack-bar 38 and its cross-head 39.

The rate-bar 17 of the scale-beam is provided with longitudinal guideways 43 and 44 in its upper and lower portions, said guideways being separated by an intervening partition 43^a. A rack-bar 45 is fitted slidably in the guideway 43, and another rack-bar 46 is fitted in a like manner within the guideway 44 of the rate-bar. An idle spindle 47 is loosely mounted in the rate-bar between the

opposing gear-formed edges of the two rack-bars, and on this spindle is a spur gear or pinion 48, which meshes with the teeth of the two rack-bars, whereby the latter are adapted 5 to travel in opposite directions simultaneously similar to the rack-bars 38 and 38^a. One of the rack-bars of the rate-bar, preferably the lower bar 46, is connected with the poise 21 of the rate-bar by the fastening 49, 10 which is adapted to travel in the slot on the under side of the rate-bar. It is evident that an adjustment of the poise 21 on the rate-bar moves the rack-bar 46 therewith, and the sliding movement of this rack-bar 46 is communicated by the intermediate idle gear to the other rack-bar 45 for the purpose of moving the latter simultaneously with and in an opposite direction to the said poise-actuated bar 46. The driven rack-bar 45 is extended into 15 the chamber of the housing or casing, and its extremity is provided with an angular arm 50, which depends from the rack-bar alongside of the headpiece 32 of the swinging frame. This angular arm 21 is provided with 20 a longitudinal slot 51, in which is loosely fitted a pin or stud 52, which is fast with the headpiece of the swinging frame, whereby the driven rack-bar is operatively and slidably connected with the swinging frame for the 25 purpose of adjusting the latter to different positions on the movement of the poise 21 on the rate-bar of the scale-beam. Although I have shown and described the rack and gear connections between the swinging frame and 30 the poise of the rate-bar, I do not desire to be confined strictly to the use of this specific connection. There is a point of advantage, however, attending the use of the oppositely- 35 movable rack-bars connected by the intermediate gear and having one member slidably 40 connected to the swinging frame to which I desire to call attention. Said advantage consists in having these parts arranged to counterbalance the gravity of the poise 21 on the 45 rate-bar, so that the latter will have no effect on the scale-beam in ascertaining the weight of the goods. In adjusting the poise 21 on the rate-bar to indicate the price per pound, it will be noticed that movement of the poise 50 to the right carries the rack-bar 46, while the intermediate gear will at the same time propel the rack-bar 45 and the arm 50 thereof to the left, this movement of the rack-bar 45 serving to correspondingly adjust the upper 55 end portions of the swinging frame and the threaded spindle thereon. It will thus be evident that the weight of the parts moving to the left at the same time that the poise is shifted to the right will have the effect of 60 counterbalancing each other, and thus the weight of the parts can be so proportioned and distributed that the adjustment of the poise will not affect the movement of the scale-beam. The arm 50 causes the movement 65 of the swinging frame to be in exact proportion to the movement of the poise 21, or, in other words, the center of gravity of the

swinging frame and the parts supported by the same will move to the left as the poise moves to the right, so that the poise may be properly 70 weighted to counterbalance the swinging frame and its parts, the excess of the weight of the poise and the rack-bar 46 over the weight of the rack-bar 45 and the arm 50 varying with the distance of the center of gravity of the 75 swinging frame and its parts from the pivot thereof. Of course the movement of the poise to the left will correspondingly actuate the rack-bar 46, which in turn will move the rack-bar 45 to the right, and thus the slotted arm 50 80 will draw the swinging frame and its parts from their inclined positions to positions more nearly at right angles to the poise-actuated spindle and in the plane of the scale-beam fulcrum. 85

It will be understood that the described connections between the poise 21 on the rate-bar and the swinging frame operate to move the upper part of the frame and the threaded spindle 37 thereon to any desired position 90 within certain limits, and this adjustment of the frame and the spindle is attained without throwing the spindle 37 out of gear with the poise-actuated spindle 27. The pitch of the threads on the two spindles 27 and 37 and the 95 size of the crown-gear and the bevel-gear are so proportioned to each other that a movement of the poise-spindle throughout the whole length of the weight-bar will cause the secondary nut 33 to travel the full length of the spindle 37. Now it is obvious that the distance 100 through which the indicator-actuating rack-bar will move, or the amount which is indicated on the dial by a movement of the weight-poise 20 at the point required to balance the scale 105 in the operation of weighing an article, will depend on the angle of the screw-spindle 37, and the angle of the spindle depends upon the position that the poise 21 occupies on the rate-bar of the scale-beam. The operator 110 slides the poise 21 to the proper graduation on the rate-bar 17 of the scale-beam, thereby adjusting the swinging frame and the screw-spindle 37 at the proper angles, and then the article to be weighed is placed on the platform. 115 The operator now adjusts the poise 20 on the weight-bar 16 until the scale is balanced, and if the goods weigh fifteen pounds the inter-gearred screw-spindles 27 and 37 will actuate the traveling nut 33 and the slotted cross-head 120 39 to move the indicator-operating rack-bar 38 a distance sufficient to move the pointer or pointers of the indicator to point to the cost of the article—namely, one dollar and fifty cents, (\$1.50.) 125

The pointers operate similar to the hands of a watch or clock—that is, when the large hand 61 makes one complete revolution the small hand 62 will be moved over one interval of space or one graduation of the inner circle 63 of the dial 64, and a second revolution of the large hand over an outer circle of graduations 65 will carry the small hand to the second graduation of the inner circle. 130

The small hand indicates the number of revolutions of the large hand, and it will be apparent that if the outer series of graduations indicate one hundred cents the hands will indicate the price of an article in dollars and cents.

The pinion 60, which is located above and which meshes with the rack-bar 38, is mounted on the inner end of a horizontal shaft 66, which carries the large hand 61, and the said shaft 66 also has fixed to it a pinion 67, which meshes with a gear-wheel 68 of a counter-shaft 69. The gear-wheel 68 is rigid with the pinion 70, which meshes with a gear-wheel 71, and the latter carries a sleeve 72, on which the small hand is mounted. The large hand is rotated directly by the rotation of the shaft 66, and the small hand is connected with the said shaft 66 by a train of gears, and this train of gears instead of being proportioned to cause the small hand to travel one-twelfth as fast as the large hand may be constructed so that the small hand will travel at a greater or less rate of speed to adapt the indicating mechanism to the character of the scale to which it is to be applied.

It will be observed that the scale-beam has its parts constructed to house the operating parts of the indicator-actuating mechanism for the purpose of protecting the elements from accumulations of dust. It is also evident that the dial of the indicator mechanism is stationary on or flat with the scale-beam, so that the dial will not be jarred or influenced by the vibration of the scale-platform by depositing the articles to be weighed suddenly thereon.

Changes within the scope of the appended claims may be made in the form and proportion of some of the parts, while their essential features are retained and the spirit of the invention embodied. Hence I do not desire to be limited to the precise form of all the parts as shown, reserving the right to vary the same.

Having thus described the invention, what I claim is—

1. In a computing-scale, the combination with a scale-beam, and an indicator carried thereby, of a weight-poise, indicator-actuating mechanism operable by said poise, a rate-poise, and mechanism actuated by the rate-poise for counterbalancing the latter and for adjusting an element of the indicator-actuating mechanism previous to operation of said indicator-actuating mechanism by the movement of the weight-poise, substantially as described.

2. In a computing-scale, the combination with a scale-beam, and an indicator having a stationary dial and carried by said beam, of a weight-poise, an indicator-actuating mechanism including a shiftable spindle and a reciprocating bar and a device actuated by the spindle and engaging the reciprocating bar, said mechanism being operatively connected with the weight-poise, a rate-poise, and means actuated by the rate-poise for counterbalanc-

ing the latter and for adjusting said spindle of the indicator mechanism preliminary to adjustment of the weight-poise, substantially as described.

3. In a computing-scale, the combination with a scale-beam, an indicator mechanism thereon, and a weight-poise, of a poise-actuated spindle, a shiftable frame, a screw-spindle carried by said frame and intergeared to the poise-actuated spindle, and a reciprocating element operatively connected with the shiftable spindle and the indicator mechanism, substantially as described.

4. In a computing-scale, the combination with a scale-beam, an indicator mechanism thereon, and a weight-poise, of a shiftable spindle supported pivotally in coaxial relation to the fulcrum of the scale-beam, means actuated by the poise for rotating said spindle, an indicator-actuator, and connections between the shiftable spindle and the indicator-actuator, substantially as described.

5. In a computing-scale, the combination with a scale-beam, an indicator mechanism, and a weight-poise, of a shiftable frame supported pivotally in coaxial relation to the scale-beam, a screw-spindle journaled on said frame, a poise-actuated spindle intergeared with the shiftable spindle, means for shifting the frame and the spindle thereon, relative to the poise-actuated spindle, and an indicator-actuator connected operatively with the shiftable spindle, substantially as described.

6. In a computing-scale, the combination with a scale-beam, an indicator mechanism, and a weight-poise, of a pivoted shiftable frame, a revoluble spindle carried thereby, a reciprocating indicator-actuator connected with the indicator and provided with a cross-head, a traveling nut slidably confined on the shiftable frame and having a geared connection with the shiftable spindle, and a slidable connection with the cross-head of said indicator-actuator, and means for changing the position of the frame and the spindle preliminary to the adjustment of the weight-poise, substantially as described.

7. In a computing-scale, the combination with a scale-beam, an indicator mechanism thereon, and a weight-poise, of an indicator-actuating mechanism operable by said weight-poise, a rate-poise, and connections between the rate-poise and the indicator mechanism, said connections being shiftable automatically, substantially as and for the purpose described.

8. In a computing-scale, the combination with a scale-beam, an indicator mechanism, and a weight-poise, of an indicator-actuating mechanism operable by the weight-poise and including a shiftable element, a rate-poise, and oppositely-movable elements intergeared together for simultaneous movement, one of said elements being connected with the rate-poise and the other element connected with the shiftable element of the indicator-actuating mechanism, substantially as described.

9. In a computing-scale, the combination with a scale-beam, an indicator mechanism, and a weight-poise, of an indicator-actuating mechanism operable by the weight-poise and 5 having a shiftable element, a rate-poise, the oppositely-movable racks, one of which is fast with the rate-poise, an idle gear intermeshing with both racks, and an arm fast with the other rack and connected slidably 10 with the shiftable element of the indicator-actuating mechanism, substantially as described.

10. In a computing-scale, the combination with a scale-beam having a slotted weight- 15 bar, an indicator mechanism, and a weight-poise, of a revoluble screw-spindle journaled in said weight-bar, a traveling nut fitted to said spindle and fast with the weight-poise, a shiftable frame, a screw-spindle journaled 20 in said frame and geared to the poise-actuated spindle, a cross-head, a traveling nut engaging with the shiftable spindle and connected slidably with the cross-head and means

for connecting the cross-head with the indicator mechanism, substantially as described. 25

11. In a computing-scale, the combination with a scale-beam having its bar 18 provided with a guideway, an indicator mechanism, and a weight-poise, of a rack-bar confined in said guideway and geared to the indicator 30 mechanism, a slotted cross-head fast with said rack-bar, a shiftable frame, a spindle journaled on said frame, a nut engaging with the spindle and having a stud fitted in the slotted cross-head of the rack-bar, means actuated by the poise for rotating the shiftable spindle, and means for adjusting the shiftable frame, substantially as described. 35

In testimony that I claim the foregoing as my own I have hereto affixed my signature in 40 the presence of two witnesses.

THOMAS A. KILLMAN.
